FIG. 2

BY

Robert L. Lemon

ATTORNEYS.

UNITED STATES PATENT OFFICE.

ROBERT L. LEMON, OF INDIANAPOLIS, INDIANA, ASSIGNOR TO VAN CAMP PACKING COMPANY, OF INDIANAPOLIS, INDIANA, A CORPORATION.

SHIPPING BOX FOR CANNED GOODS.

Application filed August 19, 1921. Serial No. 493,718.

To all whom it may concern:

Be it known that I, ROBERT L. LEMON, a citizen of the United States, and a resident of Indianapolis, county of Marion, and State 5 of Indiana, have invented a certain new and useful Shipping Box for Canned Goods; and I do hereby declare that the following is a full, clear, and exact description thereof, reference being had to the accompanying drawings, in which like numerals refer to like parts.

This invention relates to a paper or straw board box and particularly to the construction thereof.

15 The chief object of the invention is to construct a paper or straw board box for canned goods and the like in an improved manner such that the portions subjected to the greatest strain and wear in its use will be reenforced, and that the box may be constructed of but a few parts with a minimum of waste material.

20 The chief feature of the invention consists in constructing a paper or straw board box of but three parts in such a manner that the several parts cooperate with each other so as to provide a strengthened construction as well as an economical construction.

The full nature of this invention will be 30 understood from the accompanying drawings and the following description and claims.

In the drawings Fig. 1 is a perspective view of a box embodying the invention. 35 Fig. 2 is a plan view of the main box blank. Fig. 3 is a cross sectional view of the box. Fig. 4 is a sectional view of the end of the box and is taken on the line 4—4 of Fig. 1 and in the direction of the arrows.

40 In the drawings 10 indicates the bottom and 11 the side portions of the box, while 12 indicates the top flap portions. As shown clearly in Fig. 2 the top flaps, sides and the bottom are formed from an integral sheet of

45 paper or straw board and each end of the sides is provided with an end retaining strip 13, while each end of the bottom is provided with an end retaining strip 14. Each of the

aforesaid sub-divisions are integral with each other and separated by creases, these creases 50 all being formed on the same side of the sheet. This permits the simplification of the manufacturing machinery such that the main box blank may be cut from a suitable sheet and creased in the same operation. 55

There are also provided two end members, the end forming portion being indicated by the numeral 15 and the top flap portion being indicated by the numeral 16. As shown clearly in Figs. 1, 2 and 3, the main box 60 blank is folded into trough-like shape and the end strips are turned at right angles to the sides and bottom and therefore inwardly towards each other. The end blanks are positioned within the trough-like blank in 65 abuttable relation to the end strips 13 and 14 to which they are secured by the staples 17 or by any other suitable means. In this fashion it will be noted that the corners of the box include an integral edge in each instance and that the ends of the box are protected by the retaining strip, thereby greatly increasing the strength of the box. In particular, when the box is used with canned 70 goods the end piece 15 spaces the ends of 75 cans from the crease between the strip 14 and bottom 10 so that the can ends cannot reach the crease.

The invention claimed is:

A paper or straw board box comprising a 80 main body blank providing a box bottom, two sides, two top flaps, said top flaps being arranged to fold toward each other over the top of box so that their edges will abut each other, and end securing strips folded 85 over each end of each side and each end of the bottom, a pair of end blanks each providing a top flap so positioned as to fold over the top of the box so as to lie adjacent the under surface of the top flaps, and means for 90 rigidly securing said end flaps to said end securing strips, substantially as described.

In witness whereof, I have hereunto affixed my signature.

ROBERT L. LEMON.
